(57) CLAIM

The ornamental design for a shoe, as shown and described.

DESCRIPTION

FIG. 1 is a rear perspective view of a shoe showing my new design;

FIG. 2 is a side view thereof; and,

FIG. 3 is a front perspective view thereof.

The broken lines immediately adjacent to the shaded area define the bounds of the claimed design and form no part thereof. The unshaded racetrack shaped broken lines within the shaded area represent eyelets that form no part of the claimed design. The broken line within the shaded area which runs generally parallel to the lower boundary of the claim forms no part of the claimed design. The broken lines depicting the remainder of the shoe show features that form no part of the claimed design.
